H. R. VAN DEVENTER.
IGNITION DEVICE.

APPLICATION FILED OCT. 13, 1917.

Patented Jan. 6, 1920.

2 SHEETS—SHEET 2.

UNITED STATES PATENT OFFICE.

HARRY RANDOLPH VAN DEVENTER, OF SUMTER, SOUTH CAROLINA, ASSIGNOR TO
SPLITDORF ELECTRICAL COMPANY, OF NEWARK, NEW JERSEY, A CORPORATION
OF NEW JERSEY.

IGNITION DEVICE.

1,327,502.

Specification of Letters Patent.

Patented Jan. 6, 1920.

Application filed October 13, 1917. Serial No. 196,372.

To all whom it may concern:

Be it known that I, HARRY R. VAN DEVENTER, a citizen of the United States, residing at Sumter, in the county of Sumter 5 and State of South Carolina, have invented certain new and useful Improvements in Ignition Devices, of which the following is a specification, reference being had to the accompanying drawing.

10 The invention relates to new and useful improvements in ignition devices for internal combustion engines and more particularly to an ignition device including ignition electrodes, a generator and a trip-operated spring actuated mechanism, for the generator and electrodes.

An object of the invention is to provide an ignition device of the above character with a two-part supporting bracket, one of 20 which parts carries the generator and is vertically adjustable relative to the other parts to accommodate the generators where the shafts are of different heights.

A further object of the invention is to 25 provide a two-part supporting bracket of the above character wherein the part carrying the generator is mounted upon and carried by the other part which supports the electrodes and the spring-actuating mechanism and wherein the connection between the parts of the supporting bracket is such as to maintain the supporting shelf for the generator in a horizontal position independently of the clamping bolts which unite the 30 two parts of the bracket.

A still further object of the invention is to provide a two-part supporting bracket of the above character wherein the part carrying the generator may be vertically adjusted relative to the part supporting the trip lever for the purpose of varying the time of maximum current generation relative to the time of breaking the contacts of the electrodes.

40 45 These and other objects will in part be obvious and will in part be hereinafter more fully disclosed.

In the drawings, which show by way of illustration, one embodiment of my invention:

50 Figure 1 is a view partly in side elevation and partly in section showing an ignition device embodying my improvement; Fig. 2 is a front view of the same, the

generator being removed to show the actuating mechanism;

Fig. 3 is a plan view of the supporting bracket.

The invention broadly consists in an ignition device including ignition electrodes, 60 one of which is preferably movable for a make-and-break ignition. Current is furnished by a generator having a flux shifting element, which is oscillated for producing ignition current. The movable electrode and the flux shifting element are actuated by a trip lever which is moved by springs for effecting the movement of the electrode and the generator shaft. A push-rod moves the trip lever and releases the 70 same. The ignition device is supported by a two-part bracket. One of the parts of the bracket carries the electrodes, the trip lever and the springs for actuating the same, 75 while the other part of the bracket carries the generator only. The part of the bracket carrying the generator is mounted upon and supported by the other part of the bracket. The part of the bracket carrying the generator is in the form of a shelf and this shelf 80 is vertically adjustable whereby the said shelf can be properly positioned to support the generator, so that the shaft of the generator will be in alinement with the axis of the trip lever. There also may be times 85 when it is desirable to raise or lower the shelf to vary the position of the axis of the shaft of the flux shifting element of the generator relative to the axis of the trip 90 lever, for the purpose of retarding or advancing the time of maximum generation so that it may accord with the time of separating the electrodes for producing the spark.

95 Referring more in detail to the drawings which show one embodiment of the invention and my improved ignition device includes, a two-part supporting bracket, one of which is indicated at 1, and the other at 2. The supporting part 1 carries a sleeve 3, which is adapted to extend through an opening in the wall of the cylinder, which wall is indicated at W in the drawings. Mounted in this sleeve 3 are the electrodes 4 and 5. The electrode 4 is fixed while the electrode 5 is movable. The electrodes are provided with ignition points 6 and 7 which are adapted to normally contact and which

are separated for producing a spark. Also mounted on the part 1, of the supporting bracket is a trip lever 8. Said trip lever is carried by a fixed shaft 9. The trip lever is 5 provided with two pins 10 and 11. A spring 12 is attached at one end to a roller on the pin 10 while the other end is attached to a roller on the pin 13 carried by an arm 14 projecting from part 1, of the supporting 10 bracket. One end of a spring 15 is attached to a roller on the pin 11 and the other end is attached to a roller on a pin 16 which is carried by a downwardly projecting part 17 of the supporting bracket 1. 15 The trip lever is moved in a clockwise direction by a push-finger 18 which is adapted to engage a shoulder on the trip lever and release the same when the trip lever is brought to a predetermined position. This 20 return movement of the trip lever through the action of the springs serves the double function of separating the ignition points of the electrodes and operating the generator. The movable electrode 5 carries the arm 19 which lies in the path of a cam projection on the trip lever. A spring 20 bearing at 25 one end against the arm 19 and at the other end against an abutment 21 normally moves the electrode, so that the ignition points are 30 brought into contact.

The generator is indicated at G in the drawings. This generator is mounted on part 2 of the supporting bracket which is in the form of a shelf having a flat horizontal 35 surface 22. Bolts 23 passing up through the shelf are threaded into the base of the generator for holding the same in place on the shelf. The armature or flux shifting element of the generator is provided with a 40 forked arm 24 which is adapted to straddle the pin 10, so that the movement of the trip levers are imparted to the armature or flux shifting element. The part 1 of the supporting bracket is formed with a vertical 45 recess 25, while part 2 of the supporting bracket is formed by a vertical rib 26, adapted to seat in said recess 25 and to fit the same. A bolt 27 is secured to part 1 of the supporting bracket and extends through 50 a vertical slot in part 2 thereof. This bolt permits the supporting part 2 of the bracket to be vertically adjusted and holds the same in adjusted positions.

From the above description it will be apparent that the thrust of the push-finger on the trip lever and the strain incident to the actuating of the springs is carried by the part 1 of the supporting bracket. Furthermore, the generator may readily be removed 60 and also the supporting shelf therefor without in any way disturbing the trip lever and the actuating mechanism.

Then again, if any strain occurs through the movement of the armature or flux shifting element by the trip lever, it is brought

directly against the vertical rib connection between the parts of the bracket, and not against the supporting bolt for the part of the bracket carrying the generator. By loosening the winged nut on the bolt 27 the 70 supporting part 2, of the bracket may be readily adjusted. This vertical adjustment of the supporting shelf with the generator enables generators having shafts of different heights to be used. By adjusting the shelf 75 the axis of the armature shaft may be brought into alinement with the axis of the trip lever, which if the parts are properly constructed, brings about a maximum current at the time the electrodes are separated for producing a spark.

If, however, it should occur, through faulty construction, that a maximum current is not produced at the proper time, the generator shaft may be raised or lowered to 80 vary the time of maximum current generation. The trip lever and the arm of the movable electrode are perfectly formed without adjustments, so that the trip lever will strike the arm to separate the ignition 85 points at a fixed time. At this time the pin, on the trip lever which actuates the armature, will have a predetermined angular position relative to a vertical line passing through the axis of the trip lever. It will 90 be apparent that if the generator is raised to bring this axis slightly above the axis of the trip lever, the time of maximum current generation will be advanced, while if the axis of the armature shaft be dropped, the 95 time of maximum current generation will be retarded.

It is obvious that minor changes in the details of construction and arrangement of parts may be made without departing from 100 the spirit of the invention as set forth in the appended claims.

Having thus described my invention, what I claim as new and desire to secure by Letters Patent, is:—

1. An ignition device including in combination a two-part supporting bracket, a fixed and movable electrode mounted on one of said bracket parts, a generator mounted on the other bracket part, a trip lever carried by the bracket part supporting the electrodes, springs for actuating the trip lever and means whereby the part of the bracket carrying the generator may be adjusted vertically relative to the part of the bracket 115 carrying the trip lever.

2. An ignition device including in combination a two-part supporting bracket, a fixed and movable electrode mounted on one of said bracket parts, a generator mounted on the other bracket part, a trip lever carried by the bracket part supporting the electrodes, springs for actuating the trip lever and means whereby the part of the bracket carrying the generator may be ad- 120 125 130

justed vertically relative to the part of the bracket carrying the trip lever, the adjustable connection between the bracket parts including a vertical rib and a recess and 5 means for holding the parts of the bracket in various adjusted positions.

3. An ignition device including in combination a two-part supporting bracket, a fixed and a movable electrode mounted on 10 one of said bracket parts, a generator mounted on the other bracket part, a trip lever carried by the bracket part supporting the electrodes, springs for actuating the trip lever and means whereby the part of the 15 bracket carrying the generator may be adjusted vertically relative to the part of the bracket carrying the trip lever, the adjustable connection between the bracket parts including a vertical rib and recess and a 20 clamping bolt extending through a slot in one of the bracket parts to permit the parts of the bracket to be vertically adjusted and to hold the parts in various adjusted positions.

25 4. An ignition device including in combination a two-part supporting bracket, a fixed and a movable electrode mounted on one of said bracket parts, a generator mounted on the other bracket part, a trip lever 30 carried by the bracket part supporting the

electrodes, springs for actuating the trip lever and means whereby the part of the bracket carrying the generator may be adjusted vertically relative to the part of the bracket carrying the trip lever, the part 35 of the bracket carrying the generator being mounted upon and supported by the part of the bracket carrying the trip lever.

5. An ignition device including in combination a two-part supporting bracket, a fixed and a movable electrode mounted on one of said bracket parts, a generator mounted on the other bracket part, a trip lever carried by the bracket part supporting the electrodes, springs for actuating the trip 45 lever and means whereby the part of the bracket carrying the generator may be adjusted vertically relative to the part of the bracket carrying the trip lever, the part of the bracket carrying the generator being 50 mounted upon and supported by the part of the bracket carrying the trip lever, the adjustable connections between the bracket parts including a vertical rib and recess for holding the parts of the bracket in various 55 adjusted positions.

In testimony whereof I hereunto affix my signature.

HARRY RANDOLPH VAN DEVENTER.
